(57) **CLAIM**

The ornamental design for a light fixture, as shown and described.

DESCRIPTION

FIG. 1 is a bottom perspective view of a light fixture showing our new design;
FIG. 2 is a top view of the light fixture illustrated in FIG. 1;
FIG. 3 is a bottom view of the light fixture illustrated in FIGS. 1 and 2;
FIG. 4 is a right cross-sectional side view of the light fixture illustrated in FIGS. 1-3, the left side being the mirror image thereof;
FIG. 5 is a front cross-sectional view of the fixture illustrated in FIGS. 1-4, the back end being the mirror image thereof;
FIG. 6 is a bottom perspective view of another new ornamental design for a light fixture;
FIG. 7 is a top view of the light fixture illustrated in FIG. 6;
FIG. 8 is a bottom view of the light fixture illustrated in FIGS. 6 and 7;
FIG. 9 is a right cross-sectional side view of the light fixture illustrated in FIGS. 6-8, the left side being the mirror image thereof;
FIG. 10 is a front cross-sectional view of the fixture illustrated in FIGS. 6-9, the back end being the mirror image thereof;
FIG. 11 is a bottom perspective view of another new ornamental design for a light fixture;
FIG. 12 is a top view of the light fixture illustrated in FIG. 11;
FIG. 13 is a bottom view of the light fixture illustrated in FIGS. 11 and 12;
FIG. 14 is a right cross-sectional side view of the light fixture illustrated in FIGS. 11-13, the left side being the mirror image thereof;
FIG. 15 is a front cross-sectional view of the fixture illustrated in FIGS. 11-14, the back end being the mirror image thereof;

FIG. 16 is a bottom perspective view of another new ornamental design for a light fixture;
FIG. 17 is a top view of the light fixture illustrated in FIG. 16;
FIG. 18 is a bottom view of the light fixture illustrated in FIGS. 16 and 17;
FIG. 19 is a right cross-sectional side view of the light fixture illustrated in FIGS. 16-18, the left side being the mirror image thereof;
FIG. 20 is a front cross-sectional view of the fixture illustrated in FIGS. 16-19, the back end being the mirror image thereof;
FIG. 21 is a bottom perspective view of another new ornamental design for a light fixture;
FIG. 22 is a top view of the light fixture illustrated in FIG. 21;
FIG. 23 is a bottom view of the light fixture illustrated in FIGS. 21 and 22;
FIG. 24 is a right cross-sectional side view of the light fixture illustrated in FIGS. 21-23, the left side being the mirror image thereof;
FIG. 25 is a front cross-sectional view of the fixture illustrated in FIGS. 21-24, the back end being the mirror image thereof;
FIG. 26 is a bottom perspective view of another new ornamental design for a light fixture;
FIG. 27 is a top view of the light fixture illustrated in FIG. 26;
FIG. 28 is a bottom view of the light fixture illustrated in FIGS. 26 and 27;
FIG. 29 is a right cross-sectional side view of the light fixture illustrated in FIGS. 26-28, the left side being the mirror image thereof; and,
FIG. 30 is a front cross-sectional view of the fixture illustrated in FIGS. 26-29, the back end being the mirror image thereof. The broken lines shown represent portions of the light fixture that form no part of the claimed design.
